UNITED STATES PATENT OFFICE.

SAMUEL M. DARLING, OF CHICAGO, ILLINOIS.

COMPOSITION OF MATTER AND METHOD OF PRODUCING THE SAME.

1,114,590.

Specification of Letters Patent.

Patented Oct. 20, 1914.

No Drawing.

Application filed September 30, 1912. Serial No. 723,017.

To all whom it may concern:

Be it known that I, SAMUEL M. DARLING, a citizen of the United States, and resident of Chicago, in the county of Cook and State 5 of Illinois, have invented a certain new and useful Composition of Matter and Method of Producing the Same, of which the following is a specification.

My invention relates to a new and useful 10 composition of matter adapted for use as a leather preservative, and a method for producing the same.

The composition of matter referred to is produced as a by-product of lignite and is 15 found to contain creosote and anthracene, both highly preservative of leather.

The composition is produced by first distilling to dryness the oil or tar procured in the destructive distillation of lignite. The 20 fraction which comes over above 350° Fah. is redistilled to a point at which the residue has the desired consistency and waxiness. In this redistillation a measure of polymerization of the hydro-carbon molecules is 25 effected which gives the residue a much firmer body than it originally possessed. I may prefer to blow oxygen through the mass during distillation and I may also add formaldehyde to the oil to be redistilled.

I may also during redistillation add an 30 oxidizing oil such as linseed oil, in which case it is necessary to pass oxygen through the mass. The product thus obtained is light in color, not black as are the bitumens. The product can be used not only with sole, belt, harness and other rough leathers but 35 on the finest of leathers such as book bindings. This product may be added if desired after the books have been bound. The

40 product is waxy in consistency although it may be produced of any desired consistency. This composition of matter is intended for use as a preservative of leather, the creosote and anthracene content acting in that capacity in coöperation with the other constituents. The different constituents counteract the effect of surplus tanning acids remaining in the leather and in addition overcome the general tendency of the leather to putrefact. The addition of this composition

50 gives the leather more body and weight and renders it pliable and more wear resisting.

It also renders it waterproof and more resistant to surface slipping. In practice the composition is drummed into the leather at 55 a temperature from 130° Fah. to 200°, in the well known manner and takes the place of the usual fats, oils or tallow.

I claim:

1. The method of producing leather preservative, which consists in distilling to dryness the oil or tar procured in the destructive distillation of lignite, then distilling the fraction which comes over above 350° Fah., to a point at which the residue 60 has a waxy consistency, substantially as described.

2. The method of producing leather preservative, which consists in distilling to dryness the oil or tar procured in the destructive distillation of lignite, then distilling the fraction which comes over above 350° Fah., to a point at which the residue 65 has a waxy consistency, and blowing a quantity of oxygen through the boiling mass 70 during redistillation, substantially as described.

3. The method of producing leather preservative, which consists in distilling to dryness the oil or tar produced in the destructive distillation of lignite, then distilling the fraction which comes over above 350° Fah., to a point at which the residue 75 has a waxy consistency, and blowing a quantity of oxygen through the boiling mass 80 during redistillation and then adding an oxidizing oil, substantially as described.

4. A new composition of matter composed of the oil or tar of lignite distilled and redistilled to a waxy consistency, and a preservative, substantially as described. 85

5. A new composition of matter composed of the oil or tar of lignite distilled and redistilled to a waxy consistency, and an oxidizing oil, substantially as described. 90

6. A new composition of matter composed of the oil or tar of lignite distilled and redistilled to a waxy consistency, formaldehyde, and an oxidizing oil, substantially as described. 95

SAMUEL M. DARLING.
